FIG. 1.

FIG. 2.

FIG. 3.

Inventor,
Charles L. Tippett,

by John F. Tippett
his Atty.

UNITED STATES PATENT OFFICE.

CHARLES L. TIPPETT, OF WASHINGTON, DISTRICT OF COLUMBIA, ASSIGNOR OF ONE-HALF TO JOSEPH H. McCUALEY, OF WASHINGTON, DISTRICT OF COLUMBIA.

DESIGN FOR A LAMP.

55,829.

Specification for Design.

Patented July 13, 1920.

Application filed February 6, 1920. Serial No. 356,742. Term of patent 3½ years.

To all whom it may concern:

Be it known that I, CHARLES L. TIPPETT, a citizen of the United States, residing at Washington, District of Columbia, have invented a new, original, and ornamental Design for Lamps, of which the following is a specification, reference being had to the accompanying drawing, forming part thereof.

Figure 1 is an elevation of a lamp.

Fig. 2 is an inverted view.

Fig. 3 is an end view.

I claim:—

The ornamental design for a lamp, as shown.

CHAS. L. TIPPETT.
